E. BIGNELL

APPARATUS FOR REMOVING PILES

Filed May 25, 1925

Patented Oct. 4, 1927.

1,644,560

UNITED STATES PATENT OFFICE.

EDWARD BIGNELL, OF LINCOLN, NEBRASKA.

APPARATUS FOR REMOVING PILES.

Application filed May 25, 1925. Serial No. 32,541.

This invention relates to a method of and apparatus for removing piles which have been sunk or driven into the ground and particularly into the bed of a stream, although the invention is not limited to removal of piles from such a particular location.

Primarily the invention consists in jetting water along the sides of the sunken pile to remove material from frictional contact therewith, and to enlarge the hole in which the pile is located, so that the pile can be lifted out of the hole, the jets being preferably supplied from nozzles at the bottom 10 and intermediate the ends of a jetting device employed in the removing operation, the nozzle at the bottom of the device being directed downwardly to excavate around the nose of the pile, and those above the bottom 15 being directed upwardly to cause an upwardly directed flow of water to lift the solids toward the top of the hole. As the hydraulic action of the water against the sides of the pile and the sides of the hole 20 proceeds, the jetting device progressively sinks until the bottom of the hole is reached. Then certain pile-engaging means become effective to secure the jetting device to the pile so that an upward pull on the jetting 25 device will raise the pile out of the ground. Thus the present invention distinguishes materially from those jetting devices used for sinking piles, since the invention is in no wise intended as a pile sinking apparatus, 30 but as a pile removing apparatus.

The novel method by means of which I accomplish the desired results, as well as the apparatus employed in practicing the method 40 will be clearly understood by reference to the following description in connection with the accompanying drawings, in which—

Fig. 1 is a perspective view of a pile and a jetting device for carrying out the method contemplated by my invention.

Fig. 2 is an elevational view of the jetting device showing the parts in position to support the pile, and

Fig. 3 is a cross sectional view through a slightly modified form of jetting device.

Referring now to the drawings by numerals of reference:

1 designates a stream bed into which a pile 2 has been sunk to a substantial depth, but which it is desired to remove to eliminate obstruction to navigation or for what-

ever purpose. My device for removing the pile consists in its preferred form of a header 3 having radial pipe members 4, 5, 6 and 7 extending therefrom, each connected with a downwardly disposed conduit 8, 9, 10 and 11, and supported by a sling or other suitable device, shown as comprising a collar or clamp 12, the upper end of which is fastened to a ring 13 by the cable 14. Suspended from the lower end of each of the clamps 12 is a cable 15 which is connected with a dog 16 pivoted to a clamp 17 on a corresponding conduit 8, 9, 10 or 11.

The conduits are spaced apart sufficiently to enclose and move freely along the sides of a pile when the device is being positioned, and the dogs are of such length that they may drop beneath the nose of the pile when they pass thereunder, the cables 15 being of such length that they slack while the dogs are held inclined by contact with the sides of the pile during application of the device (Fig. 1), but limit setting movement of the dogs so that the latter may engage the nose of the pile when the device has been set (Fig. 2).

The lower ends of the pipes or conduits 8, 9, 10 and 11 are provided with nozzles 18 through which jets of water may be delivered to cut away the soil or gravel from around the pile and from along the sides of the hole, and with upwardly directed nozzles 19 for jetting water upwardly along the sides of the pile to step the earth or solid material upwardly to the surface of the bed to be carried off by the stream, removal of the material enlarging the hole and relieving the sides of the pile from friction of the surrounding earth so that the dogs 16 may be projected beneath the nose, and the pile freed from holding friction to permit it to be lifted.

The device is shown in Figures 1 and 2 as specifically adapted for a pile rectangular in cross section, while in Fig. 3 I have shown conduits 21 corresponding to conduits 8, 9, 10 and 11, but adapted for application to a round pile. In this modified construction three jetting pipes will ordinarily be sufficient.

It will be apparent that water may be supplied to the header through a flexible hose or pipe 22, to be distributed through the depending pipes or conduits 8, 9, 10 and 11 at uniform pressure and uniform velocity, and

then any suitable means indicated by a heavy cable 23 may be employed to lift the device and the pile to which it has been connected.

- 4. When a pile is to be removed, the device described is suspended from a crane and the hose 22 connected with a suitable pump (not shown). The device is then lowered over the upper end of the pile, the dogs pivoting
- 10 upwardly under contact with the sides of the pile. When the nozzles at the ends of the conduits reach the surface in which the pile is embedded, the pump starts and jets of water discharged from the nozzles to displace material from about the pile to allow the conduits to sink, the upwardly directed jets stepping the displaced material upwardly to the surface and maintaining a passage about the pile to allow the conduits to sink. When the ends of the conduits pass beneath the nose of the pile the dogs drop to their projected positions, and, when travel of the device is reversed, engage beneath the nose and lift the pile, jetting from the nozzles
- 15 continuing during the lifting operation to maintain the passage around the pile.

I have found that location of the upturned nozzles at sufficiently close intervals to step the material, will prevent channeling and maintain a passage entirely about the pile, thereby eliminating skin friction and requiring only sufficient power to raise the weight of the pile and the lifting device.

With my method and apparatus the pile

20 may be removed without damage to it, thereby not only eliminating it as an obstruction, but also salvaging it for future use.

What I claim and desire to secure by Letters Patent is:

- 25 1. An apparatus for raising sunken piles, comprising a jetting device consisting of a header, depending pipes carried by the header, upwardly directed jetting nozzles and downwardly directed jetting nozzles on

the pipes, and elevator dogs carried by the lower ends of the pipes.

2. An apparatus for raising sunken piles, comprising a jetting device consisting of a header, depending pipes carried by the header, downwardly directed jetting nozzles on the pipes, and vertically and laterally swinging elevator dogs carried by the lower ends of the pipes.

3. An apparatus for raising sunken piles, comprising a jetting device consisting of a header, depending pipes carried by the header, downwardly directed jetting nozzles on the pipes, the vertically and laterally swinging elevator dogs carried by the lower ends of the pipes and means for holding the dogs at a lifting angle to the pipes.

4. A pile removing device, comprising a frame consisting of a header having depending pipes provided with jetting nozzles in their side walls and jetting nozzles in their lower ends, and dogs pivotally mounted on the lower ends of the pipes and adapted for automatic movement to position for engagement with the bottom of the pile.

5. A pile removing device, comprising a frame having depending pipe members with upwardly directed water jetting nozzles and downwardly directed water jetting nozzles, means carried by the frame for engaging the bottom of the pile, and means for supplying water to the jets.

6. A pile removing device, comprising a frame having hollow depending members provided with upwardly directed jetting means and downwardly directed jetting means, and pile supporting means on the members, said pile supporting means comprising pivoted dogs and cables connected to the frame and to the dogs, whereby the dogs will be held against swinging movement below a horizontal plane.

In testimony whereof I affix my signature,
EDWARD BIGNELL.
